UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

STOP MECHANISM FOR LOOMS.

Application filed July 22, 1925. Serial No. 45,425.

This invention relates to improvements in stop mechanisms for looms of the "easy type shedding motion" in which the driving clutch is actuated by a toggle mechanism which when moved to extended position by the shipper sets the clutch in operative position and upon bang-off breaks the toggle and causes the clutch members to be disengaged.

10 In usual constructions the shipper and brake lever, which are mounted upon a common shaft, are moved from running to stopping position by engagement with the brake lever of an arm which is carried by and depends from the frog forming part of the protector mechanism.

15 In the operation of the stop mechanism this arm is sometimes broken off, or becomes loose upon the frog, so that the loom will not stop upon bang-off. Furthermore the frog is sometimes lifted from its seat by reason of unusual pressure between the arm and the brake lever, thus causing improper operation of the stop mechanism or breakage of parts.

20 The object of the present invention is to provide an improved means for releasing the clutch which acts directly upon the clutch-actuating means, thereby avoiding such breakage and other defects of the previous constructions.

25 A further object of the invention is to provide mechanism for actuating the clutch from the protector mechanism with cushioning means which will diminish the jar produced in usual stop mechanisms.

30 A further object of the invention is to provide a clutch actuating mechanism operable directly by the protector mechanism which will act through the clutch-actuating means to move the brake lever and preferably also the shipper from running position to stopping position.

35 Another object of the invention is to provide means normally connecting the shipper and brake lever which will be automatically released when the brake and shipper levers are moved from running to stopping position so that the brake can be released to permit the loom to be turned over by hand without moving the shipper towards running position.

40 Other objects and features of the invention will more fully appear from the fol-

lowing description and the accompanying drawings and will be particularly pointed out in the claims.

45 Inasmuch as the present invention relates merely to the clutch-actuating mechanism only so much of the loom structure is illustrated as is necessary to show the relation of the present invention thereto.

In the drawings.

50 Fig. 1 is a side elevation of a portion of a loom side and the mechanism embodying the present invention mounted thereon, the parts being shown in running position; and,

55 Fig. 2 is a detail plan view showing the clutch-actuating mechanism.

55 As illustrated in the accompanying drawings the main driving shaft 1 of the loom is mounted on suitable bearings upon the loom side 2 and an auxiliary frame 3 and has fixedly secured to it a gear 4 which cooperates with other gears (not shown) to 60 actuate certain of the moving parts of the loom. The gear 4 has secured to it a clutch member 5 which is adapted to co-operate with a co-operating clutch face of a driving gear 6 which is rotatably and slidably 65 mounted upon the shaft and is actuated by a suitable motor. The hub 7 of the driving gear 6 has mounted upon it a collar 8 provided with trunnions 9 which are engaged by the bifurcated end 10 of a lever 70 80 11 which when actuated moves the main gear 6 longitudinally of its shaft to cause its clutch face to engage the co-operating clutch face of the gear 4. The lever 11 is fulcrumed upon the pivoted end of an adjustable stud 12 which is mounted in a stand 85 90 13 secured to the auxiliary frame 3.

95 The lever 11 has opposite the fulcrum a cylindrically curved projection 14 which slidably engages the down-turned end of a keeper 15 which is adjustably secured by a machine screw 16 to the stand 13. The free end of the lever 11 is slotted and engages a stud 17 which extends upwardly from an arm 18 of a skeleton sleeve 19 which is slidably mounted upon a rod 20 which is fixedly mounted at its ends in the loom side 2 and the auxiliary frame 3. A spring 21, encircling the rod 20 and interposed between the end of the auxiliary frame and the adjacent end of the sleeve 19, tends normally to 100 105 force the sleeve toward the loom side, thereby normally tending to move the lever 11

upon its fulcrum in a direction to release the engagement between the co-operating clutch members.

The clutch members are forced into operative engagement in the construction illustrated herein by a toggle comprising a link 22 which is pivotally connected to a stud 23 upon a boss 24 projecting from the sleeve 19 and a co-operating toggle link 25 which is pivotally mounted upon a boss 26 on a collar 27 which is mounted on the end of the rod 20. The toggle links 22 and 25 are pivotally connected by a pin 28. A bifurcated coupling member 29 is pivotally mounted upon the pin 28 and is pivotally connected by a rod 30 to the lower end of the usual shipper 31 which is pivotally mounted on a stud 32 projecting from a shipper bracket 33 which is secured to the loom side 2. 20 The shipper 31 is in the form of a lever having a handle 34 by means of which it may be manually actuated. A brake lever 35 is fulcrumed upon the stud 32 and is provided with a downwardly extending end 36 having a lateral extension 37 which extends across the path of the shipper lever so that the shipper lever cannot be moved to starting position without actuating the brake lever to release the brake. 25 The mechanism heretofore described is of the usual character.

The protector mechanism of the loom may be of any usual character and as illustrated comprises a frog 38 which is slidably movable upon the loom side and is engaged and moved by a dagger 39 upon bang-off. In prior constructions the frog 38 is provided with an arm or finger which, upon actuation of the frog at bang-off, engages the lateral extension 37 of the brake lever and moves the brake lever and through it the shipper lever from running position to stopping position. As heretofore stated the shock produced upon bang-off sometimes broke this arm and on other occasions the resistance of the brake lever caused the frog to be lifted. 40

The present invention comprises means directly connecting the frog to the toggle mechanism or other clutch-actuating means which operates upon bang-off to release the clutch without acting upon the brake lever and shipper lever in the manner above described, thereby eliminating the likelihood 45 of breakage or improper operation of the clutch mechanism.

In the preferred embodiment of the invention illustrated herein the frog 38 is provided with a lateral extension 40 to which an L-shaped arm 41 is secured by a bolt or set screw 42. A rod 43 is slidably mounted in a suitable aperture in the depending end of the arm 41 and is provided with an abutment, such as, a washer 44 which is adjustably secured upon the rod by set nuts 45.

The opposite end of the rod 43 is in the form of an eye which embraces a pin 46 which is mounted in a bifurcated extension 47 of the pin 28 which connects the toggle links together, the eye of the rod 43 lying between such bifurcations. In order to cushion the jar which is produced by the movement of the frog at bang-off a leather washer or other cushioning member 48 is interposed between the washer 44 and the arm 41. 70 75

In the operation of the stop mechanism the frog 38 is moved by the dagger 39 in the usual manner at bang-off. This causes the arm 41 to pull upon the rod 43, which is a tension member, and through it to break the toggle from the position shown in Fig. 2. When the toggle is thus broken the spring 21 moves the sleeve 19 longitudinally of the rod 20, thus causing the lever 11, which is pivotally connected to the extension 18 of the sleeve, to rock about its fulcrum, thereby shifting the gear 6 away from the co-operating clutch member 5. Thus it will be obvious that the clutch-actuating member or toggle is actuated to 80 release the clutch members directly by the movement of the frog. The movement of the frog, in addition to breaking the toggle link, also acts through the rod 30, which is connected at one end to the pin connecting 85 the toggle links and at its other end to the shipper, to move the shipper toward stopping position.

Another feature of the invention consists in providing a detachable connection between the brake lever and the shipper which will cause the brake lever to be actuated to apply the brake when the shipper is moved to stopping position, but which connection will be automatically released when the 90 shipper reaches stopping position, so that the brake lever can be independently moved to release the brake after the loom has stopped and thereby permit the loom to be turned over by hand. 95 100 105

In the preferred construction herein the means for connecting the shipper lever to the brake lever comprises a dog 49 which is pivotally mounted upon a stud 50 upon the shipper lever and has a hook-shaped end 51 110 which engages a shouldered projection 52 extending from the brake lever toward the shipper. A stop 53 upon the shipper desirably is provided to hold the dog 49 in position to engage the projection 52 when 115 the shipper is moved toward running position. The dog 49 is provided with an oppositely extending end or tail 54 which is adapted to engage an abutment 55 projecting from the shipper stand as the shipper is moved to stopping position so that the dog 49 will be rocked out of engagement with the shouldered projection 52 when the shipper reaches stopping position, thereby freeing 120 125 130 the brake lever so that it can be ac-

tuated to release the brake after the loom has been stopped for the purpose of permitting the loom to be turned over by hand.

It will be understood that the particular embodiment of the invention shown herein is of an illustrative character and is not restrictive; that various changes in form, construction and arrangement of parts may be made within the spirit and scope of the 10 claims.

It will also be understood that the present invention is not confined to the particular clutch-actuating mechanisms which are illustrated herein, but may be applied to other 15 constructions to which it may be adapted.

It will also be understood that the invention may include other automatic means for effecting a stoppage of the loom adapted to act directly upon the clutch-actuating mechanism in the manner aforesaid instead of through the brake and snipper levers as is common in previous constructions.

Having thus described the invention, what is claimed as new, and desired to be secured 25 by Letters Patent, is:

1. Stop mechanism for looms having protector mechanism including a movable frog, a driving clutch, clutch-actuating means, and a tension member connecting said frog and clutch actuating means and acting upon movement of said frog by the dagger of the protector mechanism to release said clutch, a snipper and means connecting said snipper to said clutch actuating means operable thereby upon release of said clutch to move 30 said snipper to stopping position.

2. Stop mechanism for looms having protector mechanism including a movable frog, a driving clutch, a spring tending to release 40 said clutch, a snipper, clutch actuating means including a toggle connected to said snipper and operable when extended by the movement of said snipper to running position to set said clutch in operative position, and a tension member connecting said frog and the joint of said toggle acting upon movement of said frog by the dagger of the 45 protector mechanism to break said toggle and in conjunction with said spring to release the clutch.

3. Stop mechanism for looms having protector mechanism including a movable frog, a driving clutch, a spring tending to release said clutch, a snipper, clutch-actuating means including a toggle connected to said snipper and operable when extended by the movement of said snipper to running position to set said clutch in operative position, a rod pivotally connected to the joint of said 50 toggle and provided with an abutment to be engaged by said frog upon movement of the frog by the dagger of the protector mechanism and acting upon such movement of the frog to break the toggle and in conjunction 55 with said spring to release said clutch.

4. Stop mechanism for looms having protector mechanism including a movable frog, a driving clutch, a spring tending to release said clutch, a snipper, clutch-actuating means including a toggle connected to said snipper and operable when extended by the movement of said snipper to running position to set said clutch in operative position, a rod pivotally connected to the joint of said 60 toggle and provided with an abutment to be engaged by said frog upon movement of the frog by the dagger of the protector mechanism and acting upon such movement of the frog to break the toggle and thereby in conjunction with said spring release the clutch 65 and cushioning means intermediate of said frog and said abutment.

5. Stop mechanism for looms having protector mechanism including a movable frog, a driving clutch, a snipper, clutch-actuating 70 means including a toggle connected to said snipper and operable when extended by the movement of said snipper to running position to set said clutch in operative position, a rod pivotally connected to the joint of said 75 toggle and provided with an abutment to be engaged by said frog upon movement of the frog by the dagger of the protector mechanism and acting upon such movement of the frog to break the toggle and thereby release 80 the clutch, and means for adjusting the position of said abutment.

6. Stop mechanism for looms having protector mechanism, a driving clutch, a spring tending to release said clutch, a snipper, clutch-actuating means operable thereby when the snipper is moved to running position to set said clutch in operative position and means connected to said clutch-actuating 85 means operable by said protector mechanism to release said clutch and acting through said clutch-actuating means to cause said snipper to be moved to stopping position, a 90 brake lever and means detachably connecting said snipper to said brake lever operable 95 by the movement of said snipper to stopping position to move said brake lever to brake-applying position.

7. Stop mechanism for looms having protector mechanism, a driving clutch, a spring tending to release said clutch, a snipper, clutch-actuating means operable thereby when the snipper is moved to running position to set said clutch in operative position and means connected to said clutch-actuating 100 means operable by said protector mechanism to release said clutch and acting through said clutch-actuating means to cause said snipper to be moved to stopping position, a 105 brake lever, means detachably connecting said snipper to said brake lever operable 110 by the movement of said snipper to stopping position to move said brake lever to brake-applying position and means for automatically releasing said lever-connecting 115 120 125 130

means when the shipper reaches stopping position, whereby the brake lever may be actuated to release the brake.

8. Stop mechanism for looms having protector mechanism, a driving clutch, a spring tending to release said clutch, a shipper, clutch-actuating means operable thereby when the shipper is moved to running position to set said clutch in operative position and means connected to said clutch-actuating means operable by said protector mechanism to release said clutch and acting through

said clutch-actuating means to cause said shipper to be moved to stopping position, a latch pivotally mounted on said shipper engaging said brake lever and having a tail extending beyond said shipper and a stationary abutment positioned to engage said tail when the shipper reaches stopping position and operable to release said latch from engagement with said brake lever. ¹⁵

In testimony whereof, I have signed my name to this specification.

HARRY A. DAVIS.
